UNITED STATES PATENT OFFICE.

VALENTINE STRUBHAR, OF WASHINGTON, ILLINOIS.

SCRAPER.

1,203,936.

Specification of Letters Patent.

Patented Nov. 7, 1916.

Application filed February 23, 1916. Serial No. 79,851.

To all whom it may concern:

Be it known that I, VALENTINE STRUBHAR, citizen of the United States, residing at Washington, in the county of Tazewell and State of Illinois, have invented certain new and useful Improvements in Scrapers; and I do hereby declare that the following is a full, clear, and exact description of the invention, which will enable others skilled in the art to which it appertains to make and use the same.

This invention relates to a device for removing mud and dirt from boots and shoes. It pertains more particularly, however, to a so called "scraper" adapted to be driven into the ground or attached to a suitable support, adjacent door ways or entrances to buildings, by which persons before entering may remove the mud and dirt from their shoes.

One of the objects of the invention is to furnish a simple scraper of this nature that can be manufactured at little cost and so arranged that both the sole of the shoe and the "upper" may be thoroughly cleaned.

Another object is to construct a simple device of the nature described so constructed that the sole of the shoe may be readily cleaned and then by merely lifting the foot the upper of the shoe may be brought beneath it by which the mud and dirt may be scraped from the top.

Another object is to provide a device of the nature described for scraping the sole of the shoe and which includes also a comparatively thin wire for scraping the upper of the shoe, said wire serving to brace the entire structure and which when broken, or otherwise rendered useless, may be readily replaced by another.

To the end that the invention may be readily understood I have provided the accompanying drawing, in which,

Figure 1 is an elevation of the complete scraper. Fig. 2 is a side elevation of portions of the same showing a beveled scraping iron and the method of attaching it to one of the uprights. Fig. 3 is a side elevation of part of the device shown in Fig. 1; and, Fig. 4 is a side elevation of a slightly modified form of the same.

In the first three figures 1 indicates two upright bars preferably of metal and relatively thin, consistent with proper strength, which in the present instance are shown set in the ground but which may be secured in any

suitable manner to a support which may be portable if preferred.

2 is a cross bar secured to the uprights 1 as by riveting or bolting or any other desired method, and which if the device is to be driven into the ground, may rest or lie adjacent to the ground surface.

Above the member 2 and preferably spaced about half way between it and the upper free ends of the uprights is a cross member 3 whose ends may extend some distance each way from the uprights; being secured to said uprights in any good manner. Preferably the upper ends of the uprights and the outer ends of the said member 3 as well as the slightly projecting ends of the member 2 may be perforated as at 4, for example, and a wire 5 may be threaded through all of said perforations. For instance the end of the wire may be passed through one of the perforations of the member 2 and wrapped upon itself. From thence the wire extends through the outer end of the member 3 at that side of the device, thence through the perforation of the adjacent upright, thence across and between the two uprights and through the opposite one, thence down through the perforation of the opposite end of the member 3 terminating at the member 2 where its end is secured substantially as shown. Between the uprights the member 3 is preferably beveled so as to provide a scraping edge 6, Fig. 2.

In Fig. 4 I have shown a slightly modified form of the device. Instead of using the described perforations 4 I employ a projecting headed stud 7 projecting from the uprights 1 and the extremities of the members 2 and 3. The wire indicated in this figure by the numeral 8 in this instance is wound one or more times around each of them as indicated at 9, its terminals having the same relative position as those in Fig. 1.

In use the scraping edge 6 is employed to remove the dirt and mud from the sole of the shoe, the inner edges of the uprights 1 being used to remove the mud from the edge of the sole and side of the shoe by bringing the shoe first against one and then the other.

Where mud adheres to the top of the shoe the said shoe may be raised against the wire and moved beneath it in order to still further thoroughly clean the shoe, the angled portions outside the uprights being employed by bringing the shoe against them.

I preferably use a fairly small gage wire

so that the mud will not adhere to it but in fact will cut the mud from the shoe and cause it to directly fall upon the ground. Particularly in rural districts where it is necessary for pedestrians to traverse muddy fields or muddy roads the foot becomes covered on all sides with mud and some means is found necessary to readily and thoroughly remove it and I have found that the device described meets every requirement being very efficient in its work.

The wire when broken can be readily replaced by another in a few moments' time and as the other parts of the device are preferably of metal there is little danger of their being broken.

I desire to state that I do not wish to be confined to the exact arrangement shown and described since slight changes may be made therein without departing from the spirit and intent of the invention.

Having thus described my invention, I claim:

1. In a shoe scraper, a pair of spaced uprights, a bar extending at right angles to them and secured to each, its ends project-

ing beyond both, and a wire extending between the uprights and spaced above the bar and having terminal portions extending outwardly and downwardly at an angle and engaging the projecting ends of the bar and secured at their ends relatively to the uprights below said bar.

2. In a shoe scraper, a support, a cross-member secured relatively to it and extending beyond it at each side, a wire secured relatively to the support below the cross-member and extending upward and engaging the extended end of the latter, thence extending upward to the upper portion of the support, thence extending downward to and engaging the other extended end of the cross-member and secured relatively to the said support, said wire being spaced from the several parts of the structure to afford scraping portions for the shoe.

In testimony whereof I affix my signature, in presence of two witnesses.

VALENTINE STRUBHAR.
